UNITED STATES PATENT OFFICE.

KARL WOLLIN, OF BERLIN-CHARLOTTENBURG, AND EDUARD SMOLCZYK, OF BIESDORF-SUD, NEAR BERLIN, GERMANY.

DEVICE FOR INDICATING ADMIXTURES TO GASES AND LIQUIDS.

Application filed December 4, 1926, Serial No. 152,684, and in Germany June 27, 1925.

The present invention relates to an improved device adapted to indicate admixtures to gases and liquids, the said device being actuated by the total quantity of a definite admixture contained in a gas or liquid. It is based upon the principle of combining chemically or physically the respective admixture (or a certain part thereof) with an indicating element, whereby the latter is subjected to a change of volume or density. This change is utilized directly or indirectly for actuating an indicator, an electric switch, a valve or the like. It is also frequently necessary that such indicating element be responsive to changes of temperature.

In the drawings:

Fig. 1 shows a filter to which the invention is applied, whereby a frangible element is used.

Fig. 2 is a modified form of Fig. 1.

Fig. 3 illustrates a further modification of Fig. 1.

Fig. 4 illustrates a still further modification of Fig. 1.

As in many instances the admixture is of little avail if its degree of concentration should drop below a certain point, the indicating element in these instances must be of such nature, that it will react only on the quantity of admixture which will exceed a definite minimum quantity per unit of volume. The indicating element must be so designed that it will suffer such change of structure only after absorbing a definite quantity of the admixture, namely, by crumbling, sintering and so on, which change will actuate the indicating device. A device of this description thus possesses a definite sensitiveness and a definite capacity. The sensitiveness is given by that minimum of concentration of the admixture, above whose limit the influence upon the indicating element will only take place; and the capacity is given by that quantity of the substance absorbed that will cause the indicating device to act. Both magnitudes can be varied, the sensitiveness of the indicator by changing the quality and the capacity by changing the quantity of the substance of the indicator. Of course, the indicating element can be so designed and mounted that it will be exposed only to a certain portion of the mixture, as already mentioned.

The use of apparatus of the kind referred

to may be explained by way of example in connection with breathing filters.

Among others, catalysts, sensitive to moisture are employed for cleaning the breathing air. If the partial pressure of the aqueous vapor of the air in the breathing circuit is higher than the pressure of aqueous vapor permissible for the particular catalyst, the latter will absorb moisture to such a degree, that it gradually becomes inoperative. Apparatus employing catalysts of this kind are now furnished to advantage with devices that will notify the bearer thereof in a suitable manner of the catalyst becoming inoperative, in that said devices will act as soon as the critical quantity of moisture is present, for instance in such a manner that the breathing is opposed by an easily noticeable high resistance.

Hygroscopic substances will constitute the indicating element for indicators of the kind described adapted to be applicable here. Among these, substances are chosen whose pressure of aqueous vapor is almost equal to the critical pressure of the aqueous vapor of the substance of the catalyst. Furthermore the substance of the indicating element must be treated in such a manner, that the indicating change of structure will take place upon absorption of such a quantity of admixture, at which the mass of the catalyst will become inoperative, as shown by experience. A mode of execution of such indicating element, for instance may be as follows:

From a suitably selected hygroscopic substance a small brick is made that is mounted in the filter. Calcium oxide, calcium carbide, and phosphorus pentoxide are examples of hygroscopic substances suitable for this purpose. The said brick is adapted to crumble upon absorbing a predetermined quantity of moisture. The release of a compressed spring, for instance, caused by such action can be utilized perhaps for closing a suitable valve or the like. The hygroscopic substance must be chosen in such a manner, that it will absorb the moisture of the air passing through, only when the pressure of vapor of the latter remains above a pressure that will damage the catalyst. The size of the brick again must be so chosen, that the latter will crumble up only when the moisture of the breathing air which passed through just renders the catalyst inopera-

tive. Both facts can be ascertained empirically.

In the accompanying drawings each of the four figures is a vertical section illustrating a different typical and satisfactory form of the invention. In Fig. 1, *a* designates a portion of a filter to which the invention is applied. In a partition *b* there is provided an aperture with a sharp-edged seat *d* adjacent thereto, to co-operate with the valve *c*. On the lower side of said aperture there is provided a suitable support for the brick *f*; above the partition is a perforated cap or housing *h*, provided with a guide for the upper end of the valve stem *e*. A spring *g* presses the valve *c* downwardly and keeps the lower end of the stem *e* in contact with the brick *f*. When the brick crumbles or disintegrates, the valve will be brought upon its seat *d* and the passage of air through the filter interrupted.

In cases where it is desired to provide a device actuated by a definite change of temperature, the present invention can be adapted for this purpose too. For controlling operations or as safety-device, apparatus are often required which will react to the presence of a certain substance and also to definite temperatures or changes of temperature. Up to the present in both instances different apparatus had to be used so that the observer had to pay attention to two different signals. The union of both apparatus to one therefore constitutes an additional and essential technical advantage.

By way of example a device is described hereafter, which will actuate a signal either upon absorbing a definite amount of moisture from the surrounding air or upon reaching a definite degree of temperature. For that purpose, for instance, a spring-loaded pin or die may be used, which engages a small brick, the strength of which is reduced at a certain content of moisture of the surrounding air to such a degree, that it will be crushed by the pressure of the spring, the brick may be made of any suitable hygroscopic material, for instance calcium oxide, calcium carbide, or phosphorus pentoxide. Furthermore parts of the device as for instance the supports of the bricks or the pressure pin or die, may be made of a suitable and easily fusing metal (Wood's metal or the like). The general arrangement of parts is the same in Fig. 2 as in Fig. 1, but the supports *i* for the brick *f* consist of readily fusible metal pins. When the temperature rises to the melting point of these pins, the brick *f* loses its support and the valve *c* is closed by the spring *g*, thus again interrupting the passage of air. By a suitable selection of the metal the device may be designed to react to any desired critical temperature. At that temperature the supports will melt and the spring-pres-

sure will close the valve. If the pressure pin or die is connected with an electrical contact, the rupture or displacement of the brick will cause an electrical contact to be made, actuating a bell or the like. In Fig. 3, the brick *f* is supported upon readily fusible pins *i*, and upon the melting of these supports the spring *g* will move the rod or stem *e* and with it the pivoted hand or pointer *h* which co-operates with a scale *s*. Of course, a suitable window is provided for observing the scale and pointer. The construction in Fig. 4 is similar to that shown in Fig. 3, except that the movable member *h* is not a pointer co-operating with a scale, but a switch adapted to close the circuit *m* of a suitable electric device *X*. This may be, for instance, a motor operating a valve or an alarm. The devices shown in Figs. 3 and 4 might be arranged in a branch or by-pass of the main gas passage.

We claim:

1. A device of the class described, comprising a body having a passage for a fluid, a substantially rigid normally stationary member exposed to contact with the fluid flowing through said passage and constructed of a material affected by predetermined foreign admixtures accompanying such fluid, a movable device held stationary and inactive as long as said member remains in its initial condition but arranged to be released when the condition of said member is altered by contact with such foreign admixtures, and a device operated by the movement of said movable device when the latter is released.

2. A device of the class described, comprising a body having a passage for a fluid, a substantially rigid normally stationary member exposed to contact with the fluid flowing through said passage and constructed of a material affected by predetermined changes in the condition of said fluid, a movable device held stationary and inactive as long as said member remains in its initial condition but arranged to be released when the condition of said member is altered by changes in the condition of the fluid, and a device operated by the movement of said movable device when the latter is released.

3. A device of the class described, comprising a body having a passage for a fluid, a substantially rigid normally stationary member exposed to contact with the fluid flowing through said passage and constructed of a material affected by predetermined changes in the condition of said fluid, and a valve controlling said passage and held stationary and inactive as long as said member remains in its initial condition but arranged to be released, for closing said passage, when the condition of said member is altered by changes in the condition of the fluid.

4. A device of the class described, comprising a body having a passage for a fluid, a substantially rigid normally stationary member exposed to contact with the fluid flowing through said passage and constructed of a material affected by predetermined changes in the condition of said fluid, and a movable device held stationary and inactive as long as said member remains in its initial condition but arranged to be released for operative movement when the condition of said member is altered by changes in the condition of the fluid.
5. A device of the class described, comprising a body having a passage for a fluid, a substantially rigid normally stationary member exposed to contact with the fluid flowing through said passage and constructed of a material which will lose its cohesion upon exposure to moisture, and a movable device held stationary and inactive as long as said member remains in its initial condition but arranged to be released for operative movement when the condition of said member is altered by changes in the moisture condition of the fluid.
6. A device of the class described, comprising a body having a passage for a fluid, a substantially rigid normally stationary member exposed to contact with the fluid flowing through said passage and constructed of a material which will lose its cohesion upon exposure to moisture, a fusible support for said member, likewise exposed to contact with the fluid flowing through said passage, and a movable device held stationary and inactive as long as both said member and said support remain in their initial condition but arranged to be released for operative movement when the condition of said member is altered by changes in the condition of the fluid.
7. A device of the class described, comprising a body having a passage for a fluid, a substantially rigid normally stationary member exposed to contact with the fluid flowing through said passage and constructed of a material which will lose its cohesion upon exposure to moisture, a fusible support for said member, likewise exposed to contact with the fluid flowing through said passage, a spring urging said member toward said support, and a movable device held stationary and inactive as long as both said member and said support remain in their initial condition, but arranged to be released, for operative movement under the influence of said spring, when the condition of either said member or said support is altered by changes in the condition of the fluid.
8. A device of the class described, comprising a body having a passage for a fluid, a substantially rigid normally stationary member exposed to contact with the fluid flowing through said passage and constructed of a material affected by predetermined changes in the condition of said fluid, a movable device and means for pressing it toward said member, said device being held stationary and inactive as long as said member remains in its initial condition, but being released, for operative movement under the influence of said means, when the condition of said member is altered by changes in the condition of the fluid.

In testimony whereof we affix our signatures.

KARL WOLLIN.
EDUARD SMOLCZYK.
